US00D978141S

(12) **United States Design Patent** (10) **Patent No.:** **US D978,141 S**
(45) **Date of Patent:** **** Feb. 14, 2023**

(54) **ELECTRONIC DEVICE**

- (71) Applicant: **Samsung Electronics Co., Ltd.**, Suwon-si (KR)
- (72) Inventors: **Junyong Song**, Suwon-si (KR); **Byoungjin Kim**, Suwon-si (KR); **Woohyeok Jeong**, Suwon-si (KR); **Eunsoo Kim**, Suwon-si (KR); **Junghyun Choi**, Suwon-si (KR)
- (73) Assignee: **SAMSUNG ELECTRONICS CO., LTD.**, Suwon-si (KR)
- (**) Term: **15 Years**
- (21) Appl. No.: **29/748,580**
- (22) Filed: **Aug. 31, 2020**

(30) **Foreign Application Priority Data**

- Apr. 27, 2020 (KR) 30-2020-0018523
- (51) LOC (14) Cl. **14-02**
- (52) U.S. Cl. USPC ..... **D14/341**; D14/138 AB
- (58) **Field of Classification Search**
USPC .... D14/138 AA, 138 AB, 138 AC, 138 AD, D14/138 C, 138 G, 248, 315–318, D14/341–347, 371, 374; D6/308, 310; D10/50, 65, 98, 104.1; D18/6–7; D19/26, 59–60; D21/324, 329–330, 332; D12/114, 223
- CPC ... H04M 1/0202; H04M 1/0266; H04M 1/725
- See application file for complete search history.

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the figures illustrate portions of the electronic device that form no part of the claimed design. The dot-dash broken lines in the figures define the boundaries of the claimed design and form no part thereof.

1 Claim, 7 Drawing Sheets
